UNITED STATES PATENT OFFICE.

HARRY D. BARTLETT, OF DELAVAN, WISCONSIN, ASSIGNOR TO JULIUS KRAMER, OF CHICAGO, ILLINOIS.

SOFA-BED.

1,295,840.

Specification of Letters Patent.

Patented Mar. 4, 1919.

Application filed May 31, 1917. Serial No. 171,883.

To all whom it may concern:

Be it known that I, HARRY D. BARTLETT, a citizen of the United States, residing at Delavan, in the county of Walworth, State of Wisconsin, have invented new and useful Improvements in Sofa-Beds, of which the following is a specification.

This invention relates to improvements in sofa-beds, or, as they are commonly termed, "davenport beds," and to that particular class wherein are included a mattress-support composed of a series of articulated sections adapted to be opened into bed-form and be folded conveniently and compactly within the base of the sofa-bed frame below the seat, and a sofa-seat adapted to be supported above the mattress-support when folded and stored and to be overturned or inverted and located in front of the sofa-bed frame when the mattress-support is unfolded and disposed in bed-form.

The principal objects of the present invention are to provide a new and improved mechanism for operating to open and close the mattress-support automatically as the seat is raised and inverted or returned to its original position, as the case may be, to rigidly support said seat by means of the mattress-support and its operating mechanism when the support is folded within the base of the sofa-bed frame, to provide a back designed to become positioned in close relation with the rear edge of the seat so as to eliminate the usually present unsightly space between these two elements, and a mechanism for automatically elevating said back when the seat is moved to its initial position and the mattress-support begins its operation of opening.

Various other objects and advantages of the invention will hereinafter appear, and the novel features thereof will be particularly pointed out in the claims.

Referring to the drawings:

Figure 1 is a front elevation of a sofa-bed embodying my invention, the upholstering of the back being omitted and one of the sofa-bed frame-ends being partly broken away, the seat being closed but the back-frame elevated;

Fig. 2 is a transverse vertical sectional view of the sofa-bed frame, the back being illustrated in its elevated position, and all other parts omitted;

Fig. 3 is a partial view of Fig. 2, but illustrating the back in its lowered operative position;

Fig. 4 is a side elevation of the mattress-support unfolded into bed-form, the sofa-bed frame being illustrated by dotted lines;

Fig. 5 is a fragmentary horizontal sectional view taken on the line 5—5 of Fig. 4 and in the direction indicated by the arrows;

Fig. 6 is a view similar to Fig. 4, the parts being in the position they assume before the foot-section is lowered to form the mattress-support or after having been raised as in the act of folding;

Fig. 7 is a fragmentary plan view similar to Fig. 6;

Fig. 8 is a front elevation in detail of the mattress-support when disposed in bed-form, one end of the same being broken away; and

Fig. 9 is a detail of the mattress support in end elevation, the parts being folded and shown in the positions assumed by them when stored within the sofa-bed frame.

Similar numerals of reference indicate similar parts in all the figures of the drawings.

The conventional sofa-bed frame is employed, and therefore consists of the opposite ends 1, having front and rear posts 2 and 3 respectively, the latter being connected by the rear cross-bar 4, above which the rear posts project, as shown. A frame forming three sides of a rectangle and consisting of the opposite end-bars 5 and connecting rear bar 6, all formed of angle-iron, serves to connect the opposite ends 1, and from the center of the latter bar to points near the ends of the cross-bar 4, may extend diagonal braces 7, the whole structure constituting the back of the sofa-bed frame. A vertically disposed centrally located channel-bar 8, may be connected at its lower end to the bar 6 and at its upper end to the bar 4, the same acting as an additional brace and also serving a function hereinafter apparent. Additional vertically disposed side-bars 9, may be secured to the inner faces of the rear posts 3 and at their lower ends to the corners of the three sided rectangular frame referred to. Thus far I have described the preferred form of what is in reality the stationary part of the structure—the sofa-bed

frame—but it will, of course, be understood that the same may be varied.

Any desired construction of movable back may be employed for that hereinafter described, it being merely desirable that the back be capable of moving vertically above and so as to release the sofa-seat. In the present instance, however, as will hereinafter appear, I have provided a movable back that is capable of elevating automatically when the mattress-support begins its opening or unfolding movement, the return of the back being made by hand.

Referring to this part of the structure for the purpose of a detail explanation, it will be seen that the frame of the back comprises an upper crown-piece or rail 10, adapted to rest upon the upper ends of the rear posts 3 of the ends 1, a lower parallel rail 11, and short vertical connecting-rails 12, attached at their upper and lower ends to the crown-piece 10 and rail 11. The remainder of the construction of the back-frame may best be seen by reference to Figs. 1, 2 and 3 of the drawings. Immediately above the rear posts 3, pairs of keepers 13, are attached to the underside of the crown-piece 10, and in each pair of keepers is journaled the upper end of a supporting-rod 14, the upper end of the rod being laterally bent at an angle, as at 15, for the purpose. The vertical portions of the rods 14 are mounted to reciprocate in pairs of guides 16, through the medium of which the back-frame as a whole is raised and lowered. A coiled spring 17, one for each of the rods 14, is secured to the lower end of the rod and at its upper end to an eye 18, on the underside of the arm-piece of the end 1. These springs exert a lifting tendency and when uninfluenced serve to elevate the back-frame and the upholstery (not shown) carried thereby, as shown in Figs. 1, 2, and 3 of the drawings. Attached to the rear edge of the lower parallel bar 11 of the back-frame, are alining bearings 19, in which is journaled a shaft 20, the two ends of which, beyond the bearings, are cranked, as at 21, and journaled in openings 22, formed in the opposite vertical bars 9. Beyond the latter bars, the extremities of the shaft 20 are bent to form short cranks 23, and to the same are attached lifting-springs 24, the upper ends of which are attached to a convenient point of the stationary structure—preferably the rear cross-bar 14. It will be obvious that when the springs 24 are at that side of the bearings 22 at which they are shown in Fig. 2, they with the springs 17, will serve to support the back-frame in the elevated position illustrated. To cause the back-frame to ascend or assume its elevated position, it is simply necessary to impart to said frame at its bottom an outward swing a few inches or enough to cause the springs 24 to advance to a point in front of the bear-

ings 22. While this may be accomplished by hand and initiatory to the operation of opening or unfolding the hereinafter described bed or mattress-support, yet I prefer to accomplish the same automatically, all as will hereinafter appear. To lower the back-frame it is simply necessary to press the same downward a sufficient distance to cause the springs 24 to swing to the opposite sides of the bearings 22, when the springs 24 acting on the crank-arms 23, will serve to lock the back-frame in its lowered position above the sofa-seat.

As is usual in beds of this character, the mattress-support is conveniently formed in a series of foldable sections made of angle-iron, the sections being pivoted together in rule-joint fashion and therefore capable of folding one upon the other and of opening or unfolding to a point where they are in horizontal alinement. The number of sections may vary, but in order to secure a bed of full length and yet avoid undue width of seat, I prefer to employ a comparatively narrow head-section 26, a main-section 27, a comparatively narrow spacing-section 28, and a foot-section 29, these sections being arranged in the order mentioned, and having their side-bars overlapping and pivoted, as at 30, whereby the sections may be said to be articulated. The head-section 26 is supported wholly by the main-section 27, and the latter is lowerably supported, in this instance, by a pair of front and a pair of rear links, designated respectively as 31 and 34. The front links are forwardly curved and pivoted, as at 33, to the side-bars of the main-section 27, and at their lower ends to horizontal supporting-bars 25, formed of angle-iron, as at 32. The rear pair of links 34, are pivoted to the connecting pivots 30, between the meeting ends of the side-bars of the main-section 27 and the corresponding bars of the head-section 26, the lower ends of the links being pivoted to the aforesaid horizontal supporting-bars 25. The supporting-bars 25 may or may not be employed, but I prefer to employ them for that the mattress-support and all parts employed for operating the same thereby becomes a complete unit, may be manufactured and sold as such by the metal-bed manufacturer to the sofa-bed manufacturer or frame-maker and by the latter readily slipped into position (without the employment of skilled labor) within the sofa-bed frame. Of course, if not employed, the side-bars 5, or some other means of support with which the trade is perfectly familiar, may be substituted. In this instance, however, it will be noted that the bars 25 and 5 are positioned so that their horizontal webs or flanges are reversed—that of the bars 25 being at the upper side and those of the bars 5 at the lower side. This relatively different

positioning of these webs or flanges permits of the two sets of bars being interlocked, or, in other words, the horizontal flanges of the bars 25 rest upon the corresponding flanges 5 of the bars 5, so that the latter support the former. A pair of angular stop-clips 36, may be secured to the ends of the bars 5, and at their front ends extend above the same, so that when the bars 25 and 5 are 10 once assembled they become immovable. As a further means of connection between these two pairs of bars, angular keepers 37, may be riveted to the bars 5, with the horizontal flanges of the keepers spaced a sufficient 15 distance from those of the bars 5 to permit of the endwise insertion of the rear ends of the bars 25, the front ends of the horizontal webs of the keepers being upturned slightly for this purpose. When the bars 25 have 20 been slid endwise into position under the keepers 37 and assumed their proper position their withdrawal will be obstructed by the stop-clips 36. The foundation of the 25 mattress-support or bed-portion of the structure is thus made secure and the ease and accuracy with which it may be mounted in the sofa-bed frame will be readily appreciated.

The pivotal connections between the lower ends of the links 31 and 34 and the bars 25, 30 are, respectively transverse tie-rods 32 and 35, the same having nuts applied to their ends and serving not only as pivotal connections for the said links but also as means of connecting the two bars 25 forming the 35 foundation of the mattress-support or bed. These tie-rods 32 and 35, may be connected by means of a cross-plate 38 (one near each side of the sofa-bed frame) and between the tie-rods a short rod 39, may connect the 40 cross-plate and bar 25, thus serving not only to brace the structure but also as a means for pivoting the lower ends of a pair of links 40, to said bars 25. Each of the rods 32, 35 and 38, may have coiled about it, springs 41, (see 45 Fig. 5) the inner ends of the springs engaging the cross-plate 38 and the outer ends the rear edges of the three sets of links 31, 40 and 34, so that, when said links are swung backward, the springs are placed under tension, and when the parts hereinafter 50 described are being operated, the springs will combine to aid in such operation—that is, in raising the links to their elevated positions. L-shaped clip-plates 42, may be secured to 55 each of the track-bars 5, near the front ends of the latter, and such plates connected by a front tie-bar 43, the latter serving as the front brace for the sofa-bed frame.

A pair of opposite toggle-links 44 and 45, 60 pivoted together at their meeting ends, as at 46, have their upper and lower ends respectively pivoted, as at 47, to about the centers of the side-bars of the spacing bed-section 28 and to the tie-rod 32. A link 48, has its 65 front end pivoted at the point 46 of the tog-

gle-links and its rear end pivoted as at 49, to a point slightly above the middle of the link 40.

A leg 50, is pivoted to each of the links 44, near the upper ends of the latter, as at 51, 70 and near their lower ends are pivoted, as at 52, to the forward ends of leg operating links 53, the upper ends of which are pivoted, as at 54, to the upper ends of the 75 links 40.

Triangular eccentrics 55, are pivoted, as at 56, to the opposite side-bars of the foot-section 29, and to one of the angles of each of said eccentrics, there is pivoted, as at 58, the front end of a link 57, the rear end of 80 said link being pivoted, as at 60, to the link 61, at one side of the pivot 59, of the latter where it joins the side-bar of the foot-section 29.

Pivoted, as at 62, to the remaining angle 85 of each of the two eccentrics 55, is a link 63, and similar companion links 64, are pivoted, as at 65, to short movable standards 66, pivoted to the foot-section 29 at 59 near where the foot section joins the spacing-section 28. These links 63 and 64 are for the purpose of suspending and automatically extending and retracting the seat-frame 67, when the latter is swung out from and into the sofa-frame. (See Fig. 4.) For this 90 purpose and also to allow the seat-frame to collapse upon the folded bed, when the sofa is in use as such, the bottom of the seat-frame is provided with flared recesses (see dotted lines) and within the same the 95 said suspension-links are pivoted, as at 68. The two end-bars of the seat-frame 67, are formed with vertical recesses or guides 69, and such receive corresponding guide-bars 70, rigidly secured to and depending from 100 the side-bars of the foot-section 29.

A movable panel or filler-board 71, combines with the front of the sofa-seat 67; to close the front of the sofa-frame when the bed is folded and the seat is in position for 110 use as such, the meeting edges of the seat and board being connected by a double hinge 72, one being arranged at each end, and the two connected by a filler-strip 73. To cover the space between the hinges and the board 115 and seat, a flexible strip 74, may be used, the same being formed of the same material as the upholstery of the seat. At its rear side, the filler-board 71, has pivoted to it as at 77, a pair of short links 75, the opposite 120 ends of which are pivoted, as at 76, to the folding legs 50, near the upper ends of the latter.

The sofa-seat, which is illustrated with the usual upholstering omitted, is provided 125 with the operating loop 78.

Any desired form of bedding-clamp may be employed at the free end of the foot-section 29, for the purpose of retaining the mattress and bed-covers in position upon 130

the mattress-support or bed during manipulations of the latter. In the present instance, I have loosely journaled in the ends of the side-bars of the section 29, a transverse shaft 80, capable of rotation, and attached fast to the same is an angular or L-shaped clamping-frame 79, capable of being raised to form a foot-board, as in Figs. 4 and 8, or lowered to form a bedding-clamp, 10 as shown in Figs. 7 and 9.

Projecting rearwardly from the transverse center of the head-section 26, is a cam-shaped prong 81, the free end of which is designed to ride in the channeled guide 8, 15 for the purpose of folding the head-section of the bed as the folded sections move rearward and downward during the act of storing the same.

Angular cams 82, are secured at each corner of the foot-section 29, and project slightly in advance thereof, the lower ends of the cams being made fast to depending standards 83, formed of angle-iron, secured to said foot-section. The functions of these 20 cams are to cause an automatic raising of the movable sofa-back heretofore mentioned, such being accomplished by the cams coming in contact with the lower edge of the back when the bed has begun its unfolding movement, whereby the coiled springs 24 being thrown to the opposite sides of the bearings for the cranked shaft or rod 20, together with the springs 17, serve to elevate the back from over the seat and thereby release the bed from the seat.

Legs 84, are pivoted at their upper ends, as at 85, to the angle-iron standards 83, whereby they are adapted to fold up out of operative position along the rear edge of 40 the sofa-frame seat when the latter is in position for use as a seat, and fold down at an angle thereto to serve as a support for the outer end of the seat and the foot-section when the seat is inverted in front 45 of the structure. Any ordinary well-known means may be employed for operating the legs, as, for instance, links 84, may be pivoted at their upper ends, as at 85^a, to the foot-section, and at their lower ends to the 50 legs, as at 86, the latter being connected to the seat.

Pairs of triangular rest-blocks 88, may be located near the opposite ends of each of the side-bars of the spacing-section, the 55 same forming stops and rests when the spacing-section and the foot-section combine with the main-section to form a rectangle, as when folded. When thus folded, the head-section 26 will have assumed a substantially vertical position, and in order that it may be secured to the bed or mattress-support, so that the latter actually forms and may be handled as a complete unity, especially when being shipped, the rear edge 60 of said head-section may be provided with a

stud 89, arranged in the path of a latch 90, pivoted, as at 91, upon one side of the foot-section 29 and adapted to overlie the head-section when folded. Of course, any ordinary locking-device may be substituted for 70 that shown.

Referring more particularly to Fig. 9, wherein is illustrated in detail the mattress-support or bed folded, it will be seen that the supports for the seat-frame have collapsed so as to allow the latter to become firmly supported by the folded structure, so that, for the purpose of supporting the seat within the sofa-frame, no further means are required. It will also be seen that by reason of the folding operations of the various coacting links, the main section 27 is at the bottom and the foot section 29 is diametrically above at the top, these two sections being spaced apart by the spacing-section 28 and the stop-blocks 88. It will also be seen that the spacing-section 28 forms the front wall of the space between the sections 27 and 29, and that the head-section 26, forms the rear wall thereof, so that the four 80 sections form a rectangular space of sufficient size to receive the folded mattress and the usual covering, the latter and the several sections all being compactly folded in a comparatively small space below the seat. 90

Aided by the several springs 41, the manipulator, by grasping the loop 78, gives the initial upward movement to unfold the bed or mattress-support. As the entire structure rises upon the supporting-links 31 and 34, 100 the cams 82, abut against the underside of the back-frame, causing the latter to automatically rise, in the manner heretofore described, and to assume the elevated position in which it is illustrated in Fig. 2, wherein 105 it is locked by the springs against lowering. The head-section 26 is now unlatched from the foot-section, and as the opening operation continues, the head-section falls rearward to the inclined position shown in 110 Fig. 7, the guide 81 dropping into the channeled guide 8 of the sofa-frame, and riding down the same as the bed is further advanced in its opening operation until the head-section finally reaches a horizontal position—see Fig. 4. Through the medium of the links 40, 61 and 57, as the seat-frame and foot-section are inverted or swung outward, the triangular eccentrics 55, and standards 66 are turned on their pivots 56, 120 and 59, respectively, and through the medium of the short suspension-links 63 and 64, the seat-frame is positively extended from the foot-section, being guided in such movement by the guide-bars 70.

The opening or spreading of the links 40 and 61, through the instrumentality of the connecting-link 53, serves to swing the supporting-legs 50 outward and downward from their inoperative folded positions so 130

that they aid in the support of the middle of the bed. The outward movements of the legs, through the links 75, swing the panel 71 outward, so that the latter is suspended vertically between said legs and the adjacent edge of the sofa-seat frame. When the foot-section and seat have been wholly lowered, their outer ends are supported by the legs 84, which are swung down automatically by the links 84^a, operated by the downward movement of the seat as it separates from the foot-section.

The operation of closing is but a reversal of that just described, it being understood, of course, that the legs 84 are automatically folded by the retraction of the seat elevated to the position shown in Fig. 6. The folding operation is now continued, the bed readily breaking first at the pivotal points between the foot and spacing-sections and later at the corresponding points between the spacing and main-sections, so that the foot and main-sections are substantially parallel. As this is being accomplished, the legs 50, are automatically folded. The entire structure is now pushed rearward, in which movement, it swings upon the supporting-links 31 and 34, and is gradually lowered within the base of the sofa-frame to the position shown in Fig. 9. As the folded bed assumes this position, the rear or free end of the head-section 26 abutting against the channeled guide, is caused to swing into the position shown in said figure of the drawing, and the latch 90, which may be spring actuated, connects the head-section to the foot-section. The back-frame is now lowered by hand, so that the lower edge of the said back overlaps the upholstered seat to a substantial degree. The springs 41 resist the lowering of the folded bed structure, thus easing the latter to its lower position, and also aid in elevating the same.

It will, of course, be understood that the bed-sections support the usual wire fabric, (it not being deemed necessary to herein illustrate the same,) and that the latter will, when the sections are folded as shown, envelop the bedding.

During the folding operation, the bedding is clamped and held in position by the clothes-clamp 79, or some other form of kindred device, and, in the present instance, when the bed is unfolded for use, the clamp shown may be swung to a vertical position so as to release the bedding and also form an ornamental foot-piece.

Having described my invention, what I claim, is:

1. In a sofa-bed, the combination with the frame thereof, and opposite parallel tracks located at the ends of the frame, of a folding-bed structure, supporting-links for the same, and opposite supporting-bars to which

the lower ends of said links are pivoted, said bars being slidably applicable endwise to said parallel tracks, and means for automatically securing said bars immovably upon the tracks when applied thereto.

70

2. In a sofa-bed, the combination with the frame thereof, and opposite tracks and superimposed keepers secured to the opposite ends of the frame, of a folding-bed structure comprising opposite rest-bars applicable endwise to said tracks, and means for locking the same in position on the tracks and under the keepers.

75

3. In a sofa-bed, the combination with the frame thereof, and opposite parallel tracks located at the ends of the frame, of a folding-bed structure, supporting-links for the same, opposite supporting-bars to which the lower ends of said links are pivoted, said bars being slidably mounted upon and applicable to said parallel tracks, keepers located on said sofa-bed ends above and spaced from the tracks and overlapping the bars, and stops at the ends of the tracks and overlapping the ends of the bars.

90

4. In a sofa-bed, the combination with the frame thereof, and opposite parallel tracks formed of angle-iron and located at the opposite ends of the frame, of a folding-bed structure, supporting-links for the same, opposite supporting bars formed of angle-iron and having their angles reversely disposed to those of the tracks, said supporting-bars being slidably applicable to the tracks, pivotal connections between the lower ends of the supporting-links and the said supporting-bars, and means for securing the supporting-bars upon the tracks.

95

5. In a sofa-bed, the combination with the frame thereof, of a folding mattress-support adapted to be stored within the base of said frame and below the seat, said mattress-support consisting of a head, main, spacing and foot-sections, arranged in the order named and pivotally connected, these four sections being adapted to fold to form a rectangular closure for the bedding, means for locking the free end of the head-section to the free end of the foot-section, and mechanism for opening and closing the sections.

110

6. In a sofa-bed, the combination with the frame thereof, and an intermediate upwardly disposed guide at the back of the frame, of a sectional mattress-support, comprising a main-section and a rear pivoted head-section, supporting links for the main-section mounted in the frame and adapted to swing rearward as the main-frame is lowered into the base of the sofa-bed frame, and a curved guide located at the free end of the head-section and adapted to rest in said guide and thereby serve to bring the head-section to substantially a vertical position upon a lowering of the main-frame.

115

7. In a sofa-bed, the combination with the

130

frame thereof, of a sectional mattress-support comprising a head, main, spacing and foot-sections, articulated and arranged in the order named, supporting-links pivoted in the 5 sofa-bed frame and at their upper ends to the mattress-support and adapted to swing rearward for the purpose of lowering the support within the base of the sofa-bed frame, means carried by the latter frame and arranged 10 in the path of the rear end of the head-section for swinging said head-section to a substantially vertical position and against the end of the foot-section when the mattress-support is folded and lowered 15 and for swinging said head-section to substantially a horizontal position when the mattress support is elevated and in the act of unfolding, and means for locking the head and foot-sections together when folded 20 and lowered.

8. In a sofa-bed, the combination with the sofa-bed frame, of a mattress-support comprising a plurality of articulated sections, a sofa-seat carried by the outermost section 25 and adapted to be inverted in front of the sofa-frame, a panel for the sofa-frame carried by the seat and loosely connected thereto, and links connected with the sofa-frame and with the said panel whereby as the mattress-support is folded and the seat returned 30 to the frame the panel is caused to close the front of the frame and when the seat is inverted and positioned in front of the frame said panel is moved to open the front of the 35 latter, and links connected to the frame and to the folding mattress-support which links project through the open front of the frame, when said panel is so removed, and are adapted to operate the folding mattress- 40 support.

9. In a sofa-bed, the combination with a sofa-bed frame, of a folding mattress-support comprising articulated folding sections, a sofa-seat mounted upon the uppermost 45 section when the mattress-support is folded, links pivoted to the seat and to the said uppermost section, eccentrics pivoted to the said section, links connected to the same and the seat, and links for operating the eccentrics to lower the seat from the section when the latter is in bed-form and to draw the seat against the section when the latter is folded.

10. In a sofa-bed, the combination with a sofa-bed frame, of a folding mattress-support comprising articulated folding sections, a sofa-seat mounted upon the uppermost section when the support is folded, guide-openings formed in the seat, guide-bars extending from the section and into said openings, 55 eccentrics pivoted to the section, suspension-links pivotally connected to the seat and to said eccentrics, operating links pivoted to the eccentrics and links connected to the sofa-bed frame, the section and the eccentric operating links, whereby when the section is

unfolded the eccentrics are operated to lower the seat from contact with the section and when the section is folded to draw the seat against the section.

11. In a sofa-bed, the combination with a sofa-bed frame, of a folding mattress-support comprising articulated folding sections, a sofa-seat mounted upon the uppermost section when the mattress-support is folded, eccentric connections between said mattress-support and seat, and means for operating the eccentric connections as the mattress-support is folded and unfolded whereby to lower the seat from the adjacent section when the mattress-support is opened 80 into bed-form and to draw the seat against the adjacent section when the mattress support is folded.

12. In a sofa-bed, the combination with a sofa-bed frame, of a folding mattress-support comprising a plurality of articulated sections adapted to fold within the base of the sofa-bed frame, a sofa-seat carried by the uppermost of said sections when the support is folded, a panel-board loosely hinged 90 to the front edge of the seat and adapted to temporarily close the opening in the front of the sofa-base, a system of links for swinging the mattress-support into and out of the base and when in the latter position projecting through the opening in the base covered by the panel-board, and links connected to the sofa-bed base and to the articulated sections and panel-board, whereby, when the mattress-support is unfolded the panel-board is 100 removed from the opening in the base and becomes suspended from the inverted seat.

13. In a sofa-bed, the combination with the sofa-bed frame, of the folding mattress-support comprising the main, spacing and foot-sections, the same being articulated and arranged in the order named, links for swinging the mattress-support into and out of the sofa-base, a seat loosely mounted on the upper side of the foot-section when in 110 its folded position and adapted to be suspended therefrom when unfolded, eccentric connections between the foot-section and the seat, a system of links connected to the eccentric connections, the foot-section, and the 115 sofa-base, and pivoted legs for supporting the spacing-section and connected to and folded and unfolded by said system of links as the sections are folded and unfolded.

14. In a sofa-bed, the combination with the sofa-bed frame, of a folding mattress-support comprising the main, spacing and foot-sections, the same being articulated and arranged in the order named, links for swinging the mattress-support into and out 125 of the sofa-base, a seat loosely mounted on the upper side of the foot-section when in its folded position and adapted to be suspended therefrom when unfolded, eccentric connections between the foot-section and the 130

- seat, a panel-board loosely suspended from the front edge of the seat and adapted to temporarily cover the opening in the sofa-frame below the seat and through which the 5 swinging links extend when the bed is open, intermediate legs for supporting the sections, a link connecting each of the legs with the panel-board, and a system of links connected to the sofa-bed frame, the eccentrics 10 and legs, whereby, when the mattress-support is opened the eccentrics are operated to lower the seat, and the legs and panel-board are swung downward and the former into operative position and when the mattress-support is folded the seat is drawn against the 15 foot-section, the legs folded against the mattress-support, and the panel-board is positioned so as to close the opening in the sofa-bed frame.
- 20 15. In a sofa-bed, the combination with the sofa-bed-frame, of the main-section 27, the spacing-section 28, and the foot-section 29, pivoted together, as at 30, the swinging links 31 and 34, pivoted at their lower ends 25 to the sofa-base and at their upper ends to the main-section 27, the sofa-seat, links suspending the same from the foot-section 29, the eccentrics 55 pivoted to the foot-section and connected to the front suspending-links, 30 the legs 50, the panel-board 71 loosely connected to the front edge of the seat, the links 40, pivoted at their lower ends to the sofa-frame, the links 61, pivoted at their inner ends, as at 54, to the upper ends of the links 35 40, and at their front ends to the side-bars of
- the foot-section 29, the links 57, pivotally connected to and adapted to operate the eccentrics and at their opposite ends as at 60, to the links 61, the links 48, pivoted as at 49 to the supporting and swinging links 40, the 40 links 45, pivoted to the base and at their upper ends to the front ends of the links 48, the links 44, pivoted at their rear ends to the pivotal connections between the links 48 and 45, and at their front ends to the side-bars 45 of the spacing-section, as at 47, and as at 51, to the leg 50, and the links 75, pivoted to the legs 50, as at 76, and to the panel-board, as at 77, substantially as shown and described.
16. In a sofa-bed, the combination with 50 the main-frame, and a plurality of folding-sections forming a mattress-support and adapted to be housed within and to be unfolded in front of the main frame, of a seat loosely connected to the outermost section 55 near both its front and rear ends and adapted to become suspended therefrom and positioned thereunder when the bed is unfolded, means for automatically extending the seat from the foot-section when the mattress-support is opened and closing the same on the foot-section thereof when the bed is closed, legs pivoted to the foot-section, and links loosely connected to the legs and to the seat 60 and operated by the movements of the seat 65 for unfolding the legs as the seat is lowered from the foot-section and for folding the legs as the seat is raised against the foot-section.

HARRY D. BARTLETT.
